UNITED STATES PATENT OFFICE.

WILLIAM H. JAMOUNEAU, OF NEWARK, NEW JERSEY, ASSIGNOR TO B. F. NORRIS, ALISTER & CO., OF CHICAGO, ILLINOIS.

DESIGN FOR A SPOON.

SPECIFICATION forming part of Design No. 22,678, dated August 8, 1893.

Application filed April 6, 1893. Serial No. 469,358. Term of patent 3½ years.

To all whom it may concern:

Be it known that I, WILLIAM H. JAMOU-
NEAU, a citizen of the United States, residing
at Newark, in the county of Essex and State of
5 New Jersey, have invented and produced a
new and original Design for Spoons; and I do
hereby declare the following to be a full, clear,
and exact description of the invention, such
as will enable others skilled in the art to which
10 it appertains to make and use the same, ref-
erence being had to the accompanying draw-
ings, and to letters of reference marked there-
on, which form a part of this specification.

In the drawings, Figure 1 is a front or ob-
15 verse view of the newly designed spoon and
Fig. 2 a reverse of the same.

The leading features of the design consist
in the obverse decorations of the spoon, in the
reverse decorations of the handle, and the
20 design for a spoon substantially as herein
shown and described.

Referring again to the drawings, *a* indicates
25 the bowl, *b* the narrow part or shank of
the handle and *c* the wider part or flange of
said handle. On the obverse side the bowl
is decorated with a perspective view of the
Woman's Building, *a'* of the Columbian Ex-
position at Chicago, the shank with a space or

spaces for an inscription and the flange with
a group including a woman spinning, *c'*, a 30
globe *c''* or hemisphere and a distaff *c'''*. The
margin of the spoon handle is decorated with
conventional ornamentation *d*. The reverse
of the handle is decorated with a series of
35 panels inclosed with conventional ornamenta-
tion, the one nearest the shank presenting
the bust of a woman representing Queen Isa-
bella, the next in turn showing the seal of the
Board of Lady Managers of the World's Fair
Commission, and that at the extremity of the 40
flange a view of the ship *Santa Maria*.

What I claim is—

1. In the design for a spoon as herein shown and described, the obverse.
2. In the design for a spoon, the reverse 45
herein shown and described.
3. The design for a spoon as herein shown and described.

In testimony that I claim the foregoing I
have hereunto set my hand this 5th day of 50
April, 1893.

WM. H. JAMOUNEAU.
